UNITED STATES PATENT OFFICE.

FRANK J. HERRICK, OF NEW BRITAIN, CONNECTICUT, ASSIGNOR TO THE
NORTH & JUDD MANUFACTURING COMPANY, OF SAME PLACE.

DESIGN FOR A HEEL-PROTECTOR.

SPECIFICATION forming part of Design No. 21,888, dated October 11, 1892.

Application filed August 9, 1892. Serial No. 442,621. Term of patent 7 years.

To all whom it may concern:

Be it known that I, FRANK J. HERRICK, a citizen of the United States, residing at New Britain, in the county of Hartford and State of Connecticut, have invented and produced a new and original Design for Heel-Protectors, of which the following is a specification, reference being had to the accompanying drawings, forming a part thereof.

Figure 1 is a perspective view of a heel-protector, showing my design. Fig. 2 is a like view of the same as viewed from a different direction.

My heel-protector is of such form as will be made by bending a thin and narrow strip of

sheet metal on a traverse line at its middle, so as to present in edge view substantially a V-shaped form, leaving a wing or arm *a* on each side of the bend or point *b*, as shown in Figs. 1 and 2. The heel-protectors in said Figs. 1 and 2 are in the original drawings of about twice the size which I intend to make for general use.

What I claim is—

The design for a heel-protector, as herein shown and described.

FRANK J. HERRICK.
